Inventor:
Mabel H. Slater,
by her attorney,
Charles S. Goodwin.

UNITED STATES PATENT OFFICE.

MABEL H. SLATER, OF WEBSTER, MASSACHUSETTS.

SCOUT-BLANKET.

1,265,539.

Specification of Letters Patent.

Patented May 7, 1918.

Application filed April 7, 1917. Serial No. 160,389.

To all whom it may concern:

Be it known that I, MABEL H. SLATER, a citizen of the United States, residing at Webster, in the county of Worcester and 5 State of Massachusetts, have invented new and useful Improvements in Scout-Blankets, of which the following is a specification.

This invention relates to an improved 10 blanket particularly adapted to be used in armies as a scout blanket.

The object of the invention is to provide a blanket which may be made of soft yielding material and so arranged relatively to 15 the body of the user as to entirely envelop said body with a plurality of thicknesses of said blanket so as to form a comfortable and very warm covering which will extend entirely over the body in a plurality of 20 thicknesses and especially over the head and feet of the body. While the head of the body is covered, the blanket is so constructed as to be adapted to be folded in a manner to provide suitable ventilating and 25 breathing spaces, so that while said blanket is very warm and comfortable, it allows free circulation of fresh air to the user.

It is the object of the invention also to provide a scout blanket of the character 30 hereinbefore set forth which may also be utilized as a lap robe or as an army cape.

The invention consists of a scout blanket constructed as hereinbefore described and particularly as set forth in the claims.

35 Referring to the drawings:

Figure 1 is a plan view of my improved scout blanket.

Fig. 2 is a perspective view of the lower portion of the blanket partly folded.

40 Fig. 3 is a perspective view illustrating the blanket folded in at the lower portion and at one side thereof.

Fig. 4 is a perspective view of the blanket with the lower portion and the two sides 45 folded and joined together.

Fig. 5 is a perspective view of the obverse side of the upper portion of the blanket partly folded.

Fig. 6 is a perspective view of the upper 50 portion of the reverse side of the blanket completely folded.

Fig. 7 is a perspective view of the blanket completely folded.

Like numerals refer to like parts throughout the several views of the drawings.

In the drawings, 10 is the main body por-

tion of the blanket, 11 is an auxiliary body portion of the blanket which is attached to said main body portion on opposite sides 12 and 13 and upon the lower end 14 thereof by stitches 15. The opposite sides 17 and 18 of the main body portion of the blanket extend to a substantial distance beyond the opposite sides 12 and 13 of the auxiliary body portion of the blanket and 65 the lower end 19 and upper end 20 of the main body portion of the blanket extend to a substantial distance beyond the lower end 14 and the upper end 21 of the auxiliary body portion of said blanket. The opposite 70 sides 17 and 18 of the main body portion of the blanket are provided with snap fasteners 22.

In using the blanket the user inserts his body into the pocket 23 formed between the 75 main body portion 10 and the auxiliary portion 11 and this pocket is long enough to substantially cover the entire body of the user, with the exception of his head which projects beyond the upper end 21 of the 80 auxiliary body portion. The main body portion is now folded in the following manner: The corner 24 of the main body portion of the blanket is folded inwardly as illustrated in Fig. 1 and the lower end of the 85 main body portion is then folded across the entire width of the body portion substantially along a line A and across the entire width of said blanket, as illustrated in Fig. 2. The side 17 of the body portion of 90 the blanket is then folded over the auxiliary body portion 11 and the other side 18 of the main body portion is then folded over said body portion and over the side 17 of said main body portion which has already 95 been folded over the auxiliary body portion 11. This brings the two members of each snap fastener in alignment with each other and they are then snapped together in the usual manner, as illustrated in Fig. 4.

The folded upper end of the main body portion is then folded downwardly toward the main body portion substantially along the line B, Fig. 5, and the corners 25 and 26 spread laterally so that they extend beyond the opposite folded edges 27 and 28 of the blanket as illustrated in Fig. 5. Said corners 25 and 26 are then carried around to the back of the folded blanket, as illustrated in Fig. 6, and fastened in the position illustrated in said Fig. 6 by tapes 29 and 30 which are respectively fastened to

the corners 25 and 26, and in the completely folded position of the blanket are carried around from the back to the front thereof and tied, as at 31.

5 The manner in which the blanket is folded enables a ventilating or breathing space 32 to be formed, so that the user may have a plentiful supply of fresh air.

10 It will be noted that by extending the opposite sides and upper and lower ends of the main body portion of the blanket beyond the edges of the auxiliary body portion, it will be possible to fold said sides and edges of the main body portion of the blanket as hereinbefore set forth and in such a manner as to obtain a plurality of thicknesses over all portions of the body of the user and especially over the upper and lower portions of the body of the user.

15 20 Thus a material may be used for the blanket which is warm, flexible and comparatively thin and yet provide a blanket which may be so folded as to provide a plurality of thicknesses, especially over those 25 portions of the body which most need protection.

Having thus described my invention, what I claim and desire by Letters Patent to secure is:

30 1. A scout blanket comprising a substantially rectangular flexible body portion and a substantially rectangular auxiliary body portion attached on three sides thereof to said main body portion and forming a 35 pocket open at one end thereof to receive a human body, said main body portion extending to a substantial distance beyond said

auxiliary body portion on the opposite sides and open end thereof, whereby the opposite sides of said main body portion may be 40 folded over said auxiliary body portion and attached to each other and said end portion may be folded over toward said folded side portions, forming a breathing space, between said folded side and end portions.

45 2. A scout blanket comprising a substantially rectangular flexible body portion and a substantially rectangular auxiliary body portion attached on three sides thereof to said main body portion and forming a 50 pocket open at one end thereof to receive a human body, said main body portion extending to a substantial distance beyond said auxiliary body portion on the opposite sides and upper end thereof, and fastening means 55 attached to said opposite sides and to the upper corners of said main body portion, whereby the opposite sides of said main body portion may be folded over said auxiliary body portion and attached to each other 60 and said upper end portion may be folded over upon said main body portion and the upper corners of said main body portion fastened in folded position on the under side of said main body portion to leave a 65 breathing space between said folded upper portion and said folded side portions.

In testimony whereof I have hereunto set my hand in presence of two subscribing witnesses.

MABEL H. SLATER.
